UNITED STATES PATENT OFFICE.

JULIUS A. OLMSTED, OF MERIDEN, CONNECTICUT.

RECORDING APPARATUS.

991,532.

Specification of Letters Patent. Patented May 9, 1911.

Application filed July 20, 1908. Serial No. 444,512.

To all whom it may concern:

Be it known that I, JULIUS A. OLMSTED, a citizen of the United States, residing at Meriden, in the county of New Haven and State of Connecticut, have invented certain new and useful Improvements in Recording Apparatus, of which the following is a specification.

This invention relates to recording apparatus, the object of the invention being to provide simple and effective apparatus of such character which can be inexpensively made and which is adapted for obtaining accurate records of various kinds upon cards or other devices.

In the drawings accompanying and forming part of this specification I have represented in detail one form of embodiment of the invention which to enable those skilled in the art to practice the same will be fully set forth in the following description while the novelty of the invention will be included in the claims succeeding said description. From the statement just made it will be apparent that I do not restrict myself to the showing made by such drawings and description as I may make radical changes therefrom within the scope of my said claims.

Referring to said drawings, Figure 1 is a sectional front elevation of recording apparatus involving my invention. Fig. 2 is an end elevation of the same as seen from the right in Fig. 1. Fig. 3 is a bottom plan view of the parts shown in the preceding figures, certain parts being broken away. Fig. 4 is a front elevation of a casing suitable for inclosing the working parts of the apparatus, a part of said casing being removed. Fig. 5 is an end elevation of a portion of such casing and an indicating device carried thereby with certain adjunctive means. Fig. 6 is an elevation of escapement mechanism and a magnet co-operative therewith, the parts of the escapement mechanism and the armature of the magnet being represented as occupying different positions from those shown in Fig. 1. Figs. 7 and 8 are elevations of two of the printing-mechanism actuating-wheels, certain of the type-wheels and cooperating detents. Fig. 9 is a sectional view of the type-wheels, supporting sleeves and gears, the sustaining shaft therefor being also represented and in elevation. Fig. 10 is an elevation of a day-indicating disk, a cam co-operating there-

with being shown in dotted lines. Fig. 11 is a developed view of the printing or type wheels. Fig. 12 is an elevation of a card adapted to receive records from the apparatus. Fig. 13 is a view corresponding to Fig. 5 of a modified form of indicating means, and Fig. 14 is a view of a card which is used when the modified device is employed.

Like characters refer to like parts throughout the several figures.

The different parts of the apparatus may be sustained upon any suitable framework; that shown for this purpose is denoted in a general way by 2, and comprises several plates as 3, 4, 5, 6 and 7 generally arranged in parallelism and standing vertically. These plates are braced and tied together by pillars or cross bars. The plates 3 and 7 are connected directly to each other by superposed pillars all of which are designated by 8. (See Figs. 1, 2 and 3.) The plates 4 and 5 are connected by pillars each denoted by 9. The plates 3 and 4 are connected by pillars as 10 while the plates 5 and 7 are connected by pillars as 11. The plates 5 and 6 are connected by pillars as 12. This framework in practice is preferably rigidly mounted in a suitable casing or boxing such as that denoted in a general way by 13 and illustrated in Fig. 4. It might be stated that this casing is shown as comprising an upper enlarged portion in which the framework is directly housed and a lower portion of smaller size. The lower portion of the casing 13 may be provided with a door as 14 covering normally an opening therein and by opening which access may be had to the interior of the casing. Where a magnet is provided for effecting the action of a certain part of the apparatus this lower portion of the casing may be utilized for the reception of the battery for supplying the necessary current to said magnet. The door is preferably under lock and key, the lock therefor being denoted by 15. The upper part of the casing is shown as provided with a clock 16 serving its customary purpose.

The apparatus includes in its organization printing mechanism by which a record may be had and this printing mechanism may be of any suitable type although I find that one or more printing wheels answer my purpose and if desired and as hereinafter described and shown in the drawings the type on these wheels may be of such a nature

as to puncture the device on which the record is to be imprinted of whatever character such device may be. The machine is organized for printing a record upon a card as 5 17 shown in Fig. 12, such card when brought under the action of the printing mechanism being punctured thereby. This result may be obtained by a relative movement of the printed mechanism and the card-receiving 10 device; in the present instance it is accomplished by moving the card-receiving device relatively to the printing mechanism.

The card-receiving device is denoted by 15 18 and it is represented in Fig. 3 as occupying the space between the plates 3' and 7. The card receiving device as shown consists of a vertically-disposed chute so mounted as to be capable of movement in transverse directions. It has preferably an inward and 20 outward movement, approaching on its inward movement the printing mechanism to obtain a record and on its outward movement receding from said printing mechanism. The second movement of the card-receiving 25 device is a lateral or sidewise one this being to obtain imprints on the card of different times. For instance when the card-receiving device is at one position in its lateral travel or movement the printing mechanism 30 would indicate when a workman commenced work while when in another position the imprint would indicate the time of departure of such workman. Provision is also made on the card for securing records of time spent 35 on overtime work. These are not matters of consequence for the apparatus could be modified to obtain other records or it might be employed simply to secure a single record; that is the time of arrival and departure of a workman on a particular day. The card receiving device has a flared mouth at the upper end thereof by which a card can easily be introduced thereto the card moving downward until its progress is arrested 40 by a time-controlled stop as will hereinafter appear, such stop automatically defining the position of the card to receive the record of a particular day. This stop as will also hereinafter appear is advanced step by step 45 one step corresponding to one half of a day.

From the sides of the card-receiving device 18 there project laterally-extending arms as 19 four of such arms being shown and each being equipped with an anti-friction roller as 20. These arms are so disposed that there are upper and lower pairs thereof. The rollers 20 for the upper arms 19 are represented as bearing against the under side of a cross bar as 21 while the lower 50 rollers bear against the upper side of a companion cross-bar as 22, the two bars being disposed in parallelism and presenting a traveling carrier or carriage for the card-receiving device or chute 18. As shown 55 in Fig. 3 these cross bars 21 and 22 have

longitudinal slots as 23 through which the card-receiving device is passed downward and in which the latter moves in a sidewise direction so as to change the lateral relation of the card with respect to the printing mechanism. The cross-bars 21 and 22 are shown as provided with wheels as 24 adapted to roll in grooves as 25 in blocks as 26 on the plates 3 and 7 during the movement of the card-receiving device toward or from the 70 printing mechanism. The card-receiving device or chute therefore is easily moved in transverse directions. The means for moving the same will be hereinafter set forth.

In the present instance the printing mechanism includes three type wheels as 27, 27' and 27'' each wheel as will hereinafter appear being given a step by step or intermittent movement. The wheel 27 (see Figs. 9 and 11) is the minutes wheel having on its 80 periphery puncturing type running from 0 to 9. The wheel 27' is the fractions of hours or tens of minutes wheel, it having two series of peripheral type running each from 0 to 5 while the hours wheel has peripheral type running from 1 to 12. The wheel 27 is given one step each minute, the wheel 27' is given one step each ten minutes while the wheel 27'' is given one step each hour. The type are so arranged on the several wheels that they will be accurately aligned at the printing point which as will hereinafter appear is at a place coincident with a slot in the card-receiving device 18. The three printing-wheels 27, 27' and 27'' 90 are fastened to sleeves as 28, 29 and 30 respectively, the sleeves 28 and 29 being freely rotative on the arbor or shaft 31 while the sleeve 30 is freely rotative upon the sleeve 29 by virtue of which said wheels can be 100 easily independently rotated. The shaft 31 is supported by and between the plates 4 and 5. The printing wheels are held from lateral motion by spacing collars each denoted by 32 on the arbor or shaft 31 as 105 shown clearly in Fig. 9.

The wheels 27, 27' and 27'' are operated respectively by actuating wheels as 33, 34 and 35 rigidly fastened in some suitable manner to the shaft 36 rotatively supported by the plates 4 and 5 as shown best in Fig. 3. The minute hand of the clock 16 can be fastened to the extreme outer end of the arbor or spindle 36 which constitutes the main shaft of the apparatus. The wheel 33 is 115 provided with sixty peripheral teeth which mesh with the teeth of a pinion as 37 fastened to the sleeve 28. The wheel 34 has six peripheral teeth and co-operates with a pinion as 38 rigid on the sleeve 29. The wheel 35 has but a single tooth and coacts with a pinion as 39 rigid with the sleeve 30. The wheel 27 is given one complete turn and coincident with the final step thereof the wheel 27' is moved forward one step. 130

When the wheel 27' is making its final step the wheel 27" is being moved forward simultaneously one step, the teeth of the three actuating wheels 33, 34 and 35 being 5 so related as to secure such operation. In other words while the three wheels move synchronously the wheel 27 is moved each minute, the wheel 27' each ten minutes and the wheel 27" each hour by reason of the 10 number and relation of the peripheral teeth on the actuating wheels 33, 34 and 35 which latter as will be hereinafter pointed out are time controlled. The pinions 37, 38 and 39 it might be stated have ratchet-teeth.

15 I provide means for preventing positively accidental movement of the three type or printing wheels 27, 27' and 27" and the means shown for this purpose will now be described. Rotative with each of these three 20 wheels is a disk as 40, said disks being rigid with the sleeves 28, 29 and 30 and each having peripheral notches as 41 adapted to receive the effective portion of a tooth on one arm or branch of an angular detent as 42.

25 It will be understood that there are three of these detents and they are represented as loosely carried by a shaft or spindle as 43 supported by and between the duplicate plates 4 and 5. Normally the teeth of the 30 respective detents are fitted in notches in the coöperating stop disks 40, this relation being maintained by coiled torsional springs 44 acting against the respective detents and connected with collars as 45 on said shaft 35 or spindle 43. Each of the wheels 33, 34 and 35 coöperates with a detent 42 and releases the same. For example when the wheel 33 moves the coöperating detent 42 to its inoperative position, the printing or 40 type wheel 27 may be operated and the same applies to the wheels 34 and 35 and their detents. The wheel 33 through its peripheral teeth actuates the detent 42 associated therewith. The wheel 34 is provided with 45 lateral pins or tappets 46 for operating its detent 42, such pins corresponding in number with the peripheral teeth of said wheel 34 and it follows that the wheel 35 has but a single lateral pin as 47 for operating its 50 detent 42. Each detent is operated to its type-wheel releasing position at the correct moment and is returned to its original or operative position by the power of its spring 44. The detents therefore also prevent over- 55 throw of the respective printing wheels.

The three wheels 33, 34 and 35 are in the present instance intermittently operated by imparting to the shaft 36 to which they are rigidly connected a step by step movement, each step covering an interval of one minute. It naturally requires one hour for said three wheels and shaft to make a full or complete rotation. The means for operating the shaft although governed as to 60 time through the intervention of clock-work

is not directly operated by clock-work but is operated by a motor controlled by clock-work or rather by escapement-mechanism controlled in turn by clock-work as will hereinafter appear. I will hereinafter 70 describe a suitable motor for operating the shaft 36 and escapement mechanism for governing the action of the motor. By operating the said shaft from a motor I can employ a clock of small power for governing the action of the machine; as a matter of fact such a clock can govern several of the apparatus, the operating of the latter being done by their inclosed motors.

The motor to which allusion has been 80 made, includes in its make-up a spring as 48 of coiled form surrounding the arbor or shaft 49 one end of the spring being fastened to said shaft and the other end to one of the pillars 12; said arbor or shaft 49 85 being rotatively supported by the plates 4, 5 and 6. The connection of said spring with said arbor is the same as that found in clocks as in the case of the main springs thereof. Fastened to the outer end (Fig. 1) of the 90 arbor 49 is a ratchet-wheel 50 engageable by a spring pawl as 51 pivoted to the gear-wheel 52. The arbor has a squared end as shown in said figure to receive a key for putting said spring 48 under tension or 95 for winding the same. The power of the spring is applied to the ratchet-wheel 50 and by the latter to the pawl 51 which is the final factor for applying the force of the spring to the gear or motor wheel 52. 100 The squared end portion of the arbor 49 it might be stated projects through the front wall of the casing 13 as indicated in Fig. 4. The circumferential teeth of the gear or motor wheel 52 mesh with a pinion as 53 105 fastened to the shaft 36. The normal tendency of the gear or motor wheel 52 is to turn and said wheel is caused to turn step by step or intermittently under the control of escapement mechanism each step occupying one minute. It follows that each time the wheel 52 turns the wheels 33, 34 and 35 are simultaneously turned through the agency of the intermediate parts.

110 Loosely carried by the arbor or shaft 36 is an elongated sleeve or tube 54 to the inner end of which is fastened a gear wheel 55 meshing with a pinion 56 rotative upon the stub shaft 57 supported by the plate 4. The said stub shaft also rotatively carries a gear 57', the gear 57' and pinion 56 being rotative with each other; for example by being connected together. The gear 57' meshes with a pinion 58 fastened to the shaft 36. The pinion 58 is the first member and the 120 gear 55 the final member of a train of intermeshing gears they being so proportioned as to secure a twelve to one ratio between the shaft 36 and sleeve 54 by reason of which through the medium of devices hereinafter 125 130

described the sleeve 54 will be made to turn once in each twelve hours. I have shown as fastened to said sleeve 54 a cam 59 having a let-off or releasing portion or face 60 joining 5 the parts of least and greatest radius. It is therefore apparent that this cam is given one complete turn each twelve hours. Coöperative with the cam 59 is an angle lever 61 supported for oscillation upon the outside of 10 the plate 4, the upper arm of said lever being shown as provided with an offset 62. It might be stated that at 12.01 Monday a. m. the offset 62 will bear against the portion of least radius of the cam and also against the 15 releasing face or shoulder 60 of said cam. As the cam rotates step by step the upper arm of the angle lever 61 is gradually swung toward the left in Fig. 1 the movement continuing until the offset reaches the point of 20 greatest radius of the cam surface immediately beyond which point or just at the conclusion of one complete rotation of said cam the said angle lever is released thereby so that the angle lever can be returned to its 25 original position with the offset against the point of least radius of the cam, this releasing operation occurring at twelve midnight Sunday. The operations described are repeated each twelve hours. In the description 30 just given I started with 12.01 Monday a. m. and commencing with this time and ending with Monday at noon, a dial hereinafter described would indicate Monday a. m., while after Monday noon until Monday midnight 35 such dial would indicate Monday p. m. To the upper arm of the angle lever 61 is connected a pull-spring as 63, the other end of said spring being connected with a stud or pin as 64 projecting outward from the plate 40 4. When the upper arm of the angle lever 61 is swung to the left in the manner previously indicated the spring 63 is stretched whereby when said arm is released it can be instantly returned to its original position 45 with the offset 62 traversing the releasing face 60 by the power of said spring 63.

The two plates 4 and 5 support an arbor 65 which loosely carries a sleeve 66 of some length. To the outer end of this sleeve is 50 fastened a dial 67. To the sleeve are also fastened a stepped snail cam as 68 and a ratchet-wheel 69. The function of said cam 68 will be hereinafter described. To prevent retractive movement of the rotary sleeve 55 66 and the three parts rigidly carried thereon I may provide a spring-actuated pawl 70 pivoted upon the plate 4 for engaging the ratchet-wheel 69. The lower arm of the angle-lever 61 is shown as pivotally supporting a spring-controlled pawl 71 for operating intermittently the ratchet-wheel 69. During the time that the upper arm of said 60 angle lever 61 is being swung to the left in Fig. 1 as hereinbefore set forth, the lower 95 arm thereof is being oppositely moved. Nothing results from this so far as the pawl 71 is concerned owing to the fact that said pawl is yieldably mounted. When, however, the angle lever 61 is released as hereinbefore described the lower arm thereof can 70 be swung to the left in said Fig. 1 by the power of the spring 63 and during such swing the pawl 71 is adapted to turn the ratchet-wheel 69 a distance equaling one tooth thereof. It naturally follows that the 75 dial 67 and cam 68 are moved like distances. In other words said dial and cam will be each moved at the close of each twelve hours of the day. The rotary dial, disk or indicating device 67 has on its outer face fourteen 80 equally-spaced divisions printed with suitable characters to indicate half divisions of a day; for example such as Sunday a. m., Sunday p. m., and so on for the rest of the week. The indicating symbols on this dial 85 or disk can be seen and read through a sight opening or slot as 72 in the casing 13 as shown in Fig. 4. Each time therefore that the main shaft 36 turns twelve times the dial 67 is moved once and for a distance corresponding to that between two of the indicating divisions thereof.

It will be remembered that I have referred to a stop which controls the vertical position of the card to be printed whereby such 95 card may receive on it the proper imprint of the division of the day on which work is done. A stop that answers my purpose is shown at 73 and consists of a bar projecting entirely across and outwardly beyond 100 the card-receiving device 18, the latter having vertically elongated slots in its opposite side walls for the passage of said stop or bar on which the lower edge of the card 17 is adapted to rest during the printing operation. This stop is preferably fed upwardly 105 by the cam 68 acting through intermediate devices which will now be described. At the opposite ends of said stop or bar 73 are fastened the two horizontal guide members 110 74 which receive the anti-friction rollers 75 carried rotatively at the outer ends of the like levers or arms 76, the inner ends of said levers or arms being fastened to a rock-shaft 77 supported by the plates 4 and 5, one of 115 said levers being in proximity to the cam 68. The operative face of said cam 68 is adapted to engage a pin or projection as 78 fastened to the adjacent lever or arm 76. Projecting from said shaft 77 is a finger 79 120 to which is connected one end of a pull spring as 80 the other end of said spring being connected with the plate 4 and said spring serving to maintain the projection or stud 78 solidly against the stepped surface 725 of the cam 68. When the stop or bar 73 is in its lowest position as shown in Fig. 2, the projection or stud 78 will be in contact with the lowest part of the cam 68. If therefore a card such as that represented in Fig. 12 130

be inserted into the receiving device or chute 18 the card can be entered its maximum extent so as to bring the upper line of the first division of the first day opposite the printing point. When the cam 68 is fed one step as hereinbefore described, the arms or levers 76 are elevated so as to raise the stop 73 a distance equaling one of the vertical half day divisions or spaces of the card 10 whereby the lower division of the first week day will be brought opposite the printing point. The stop 73 is elevated step by step each step occurring at the close of each twelve hours of each day. The cam 68 when 15 it has completed one rotation, which it requires one week to do, will release the two levers 76 whereby said levers can be promptly returned to the position they are shown as occupying in Fig. 1, by the power of the 20 spring 80 assisted by the weight of said levers.

By a lateral movement of the card-receiving device or chute 18 I may print on the card the time of arrival and departure of a 25 workman during regular or overtime work and I provide readily accessible means for moving said card-receiving device laterally and for also indicating its correct positioning as will now appear.

30 I have shown as fastened to the card-receiving device 18 on the outside thereof a rack-bar 81 the teeth of which are in mesh with a pinion 82 fastened to a spindle or shaft 83 supported for rotation by bearings 35 or brackets as 84 supported by and between the plates 3 and 7. The outer end of said spindle or shaft 83 is shown as squared to receive an arm 85 presenting a means for operating said spindle and also a pointer or 40 index device, the motion of said arm being limited by stops as 86 on the exterior of the casing 13. On the casing are printed the words "In" and "Out" in duplicate. In other words there are two divisions each including one of said words and each division is marked by something to indicate the time whether regular or over. In the present case the words "In," and "Out" at the left in Fig. 5 indicate regular time while the corresponding words on the right denote overtime. In radial coincidence with the words "In" and "Out" are sockets as 87 to receive a spring-controlled stop pin as 88 carried on the arm 85. In Fig. 5 the stop pin 55 88 is occupying the first of the four sockets 87 the pointed end of the arm 85 at this time being opposite the word "In" of the two divisions of the indicating device comprising the several printed words shown in said Fig. 5. At this time also the card-receiving device 18 will be at the extreme left end of its lateral stroke in Fig. 2 so that with the stop 73 occupying the position it is shown in Fig. 2 the card 17 if resting on said stop 65 would receive an imprint in the space A

thereof, were the device 18 so operated as to obtain such an imprint. The workman on leaving his work at the close of his regular day will swing the arm 85 over until the pointed end of said arm registers with the word "Out" in the regular time division and if after this his card be inserted into the card-receiving device 18 and the latter operated to obtain an imprint the said imprint would appear in the space B of the time card owing to the fact that when the arm 85 was swung over as set forth the card-receiving device 18 through the intermediate parts, was moved laterally or toward the right in Fig. 2. By a further lateral movement of said card toward the right I can obtain imprints of extra time work. If desired and as shown the several characters "In" and "Out" and "Regular time" and "Over time" can be printed directly upon the exterior of the casing 13.

Except for their rotary movement the printing or type wheels 27, 27' and 27" are immovable and impressions of said wheels or the three aligned type thereof at the printing point are obtained as it is believed will be apparent, by moving the card-receiving device 18 toward the printing wheels. For obtaining this operation an actuator or presser device such as that designated in a general way by 89; said actuator being shown as consisting of a bifurcated arm loosely supported for oscillation by a shaft as 90 extending between and supported by the plates 3 and 7. The head or upper portion of the oscillatory or swinging actuator 89 is provided on the inner side thereof with a block as 91 which serves to move the card-receiving device inward on the inward swing of said actuator whereby the type of the three wheels can be projected through the inner of the opposite slots 92 in the inner and outer walls of the card-receiving device or chute to thereby make an impression upon the card. The card-receiving device 18 is returned to its original or normal backward position by a coiled spring as 94 connected therewith.

Between the plates 3 and 7 I have shown as mounted a shaft 95 upon which is rotative a sleeve 96. Fastened to said sleeve in an eccentric manner is the disk 97 located to engage the upper portion of the actuator 89. To the rocking sleeve is also fastened the operating hand lever 98 which is operated by the workman to obtain an impression on his time-card. In Fig. 1 the cam-disk 97, hand-lever 98, card-receiving device 18, and actuator 89 are represented in their retracted positions. If the lever 98 be swung down the cam-disk 97 will swing the actuator 89 inward whereby the latter will thrust the card-receiving device 18 inward to secure a record. The actuator 89 is returned to its original or normal position by a 130

spring as 89' connected therewith while the cam-disk 97 and hand-lever 98 are returned to their primary positions by a spring 99 connected with a lug as 99' on the sleeve 93 5 all as illustrated in said Fig. 1.

As will now appear I prefer to effect the action of an alarm on each operation of the apparatus, and this alarm is preferably of audible character, a bell sufficing my purpose, as will hereinafter appear as will also the means for actuating said bell. Such a bell is shown at 100 and it is fixed in some suitable way to the plate 7, being operable by a hammer as 101 extending from a sleeve 15 102 loose on the pin 103 projecting from the plate 7 as shown in Figs. 1, 2 and 3. At opposite sides of the pin 103 are parallel pins or studs 104 and 105 connected by a strip 106. The sleeve 102 has projecting 20 arms 107 and 108, the arm 107 constituting a stop-arm and being co-operative for this purpose with the pin 104 while the arm 108 is engageable by a spring pawl as 109 pivoted to a plate 110 fastened to the outside of 25 the actuator 89 as best shown in Fig. 1. Around the sleeve 102 is a coiled spring 111 one terminal whirl of which is projected against the pin 104 while the other terminal whirl of which acts against the hammer 101. 30 When the actuator 89 is swung inward in the manner previously described the pawl 109 is moved therewith and acting against the arm 108 swings the arm 108 inward and thereby elevates the hammer 101, the spring 35 111 being put under tension. When the inward stroke of the actuator 89 is practically completed the pawl 109 will pass free of the arm 108 thereby releasing the hammer 101 so that the free portion of the hammer can be 40 projected forcibly against the bell 100 to sound the same, the arm 107 being arrested by the pin 104. On the outward stroke of the actuator 89 the pawl will engage over the arm 108. 45 Any suitable escapement mechanism may be provided for governing the action of the several actuating wheels 33, 34 and 34 and the spring-motor wheel 52. I have found the escapement mechanism shown best in 50 Figs. 1 and 6 as satisfactorily answering my purpose, said mechanism being represented in its two shifted positions in said two figures. While the escapement-mechanism may be operated in any desirable manner I prefer to use an electro-magnet, as will hereinafter appear. This magnet is energized preferably each minute by the aid of 55 clock mechanism which I have not illustrated as it forms no part of my invention. 60 The clock mechanism if desired may be common to several of the apparatus and it may be provided with means for causing each minute the energization of such a magnet, which may be of any suitable type although 65 that hereinafter described is advantageous.

The escapement mechanism includes in its construction a shaft as 112 supported for rotation by the plates 4 and 5 as shown in Figs. 1 and 6 and also in Fig. 3. Loosely mounted on said shaft is a pinion 113 the teeth of which mesh with those of a segment 114 on an arm 115, projecting from the armature 116 of the magnet 117. The armature is pivotally mounted to swing about an axis located midway between the poles of said magnet 75 and the inner end of the arm 115 is connected with said armature at its center of motion. In Fig. 1 the parts are shown as occupying their normal positions the magnet at this time being deenergized or dead. 80 When said magnet is energized its armature is moved to the position it is shown as occupying in Fig. 6 with the terminals of the armature squarely across the poles of said magnet. During this action the arm 115 is 85 swung upward and the segment on such action is caused to partially turn the pinion 113. When the magnet is deenergized the arm is by its weight caused to return to its original position carrying therewith the 90 armature. There is also loose on or rotative about said shaft 112 a disk 118 to which is shown as pivoted a spring-controlled or yieldable pawl 119. The disk 118 and the pinion 113 are adapted to turn together and 95 for this purpose they may be fastened to each other in any suitable way. The pawl is illustrated as engaging a ratchet-wheel 120 loose on the shaft 112 and provided on 100 a side face with several laterally-extending pins 121 the function of which will hereinafter appear. When the segment 114 is operated as hereinbefore stated the pinion 113 is turned as is the disk 118 whereby the pawl 119 becomes operative for advancing the ratchet-wheel 120, the parts being so proportioned that on each operation of said segment the ratchet-wheel is fed a distance agreeing with the length of one tooth. On 105 the return movement of the segment the pawl rides idly over the toothed periphery of the ratchet-wheel. The ratchet-wheel 120 with its laterally-extending pins 121 presents in effect a lantern wheel and co-operates with the spur-wheel 122 rotatively mounted on a pin 124 on the plate 4, a disk as 125 being rotative with said spur-wheel, for instance, by being fastened to the hub of 110 said spur-wheel. The latter as will hereinafter appear is oscillatory and overthrow or accidental movement thereof is prevented by a spring-brake as 126 engaging a side face of said disk 125. The spur-wheel 122 cooperates with a lantern-wheel 127 fastened to the shaft 128 rotatively supported by and between the plates 4 and 5. To said shaft 128 is fastened a pinion 129 the teeth of which are in mesh with the gear 130 fastened to the main shaft 36 as best shown in Fig. 3. (See also Fig. 1.) There is also 115 120 125 130

fastened to said shaft 128 a gear 131 meshing with a pinion 132 fastened to the shaft 133 supported rotatively by and between said plates 4 and 5. To said shaft 133 is fastened 5 a gear 134 meshing with the pinion 135 on the shaft 136 carrying a fan 137 constituting a suitable governor for the escapement mechanism. By virtue of the relative sizes between the gears just described the fan 137 10 is caused to rotate at a very high speed on the release of the escapement mechanism.

Fastened to the armature at approximately the axis of motion thereof are arms 138 and 139, the arm 138 coöperating with 15 a projection as 140 on the governor or fan shaft 136 and having a hook for this purpose while the upper arm constitutes an actuator for the two levers 141 and 142 which swing together and which for such purpose may be 20 connected to each other, said levers being pivoted upon the plate 4. The free portion of each of said levers is provided with a hook and each as will presently appear constitutes a detent. It might be stated that 25 the hooked arm 138 also acts as a detent for the fan 137. Normally or when the parts of the escapement mechanism are at rest the hook at the free end of the lever 142 stands against and in the path of a pin 143 on the 30 side of the gear 134 to thereby prevent the escapement mechanism from operating; that is the escapement mechanism is normally locked against action. When, however, the lever 141 is lifted to carry the hook thereof 35 free of said pin 143 said escapement mechanism is released as is also the spring operated gear or motor wheel 52 whereby the latter can exercise its function of effecting through the intermediate parts the action of 40 the printing mechanism although as will be clear only one of the wheels of the printing mechanism may be operated while it is possible that all three of them may be turned together.

45 When the parts of the escapement mechanism are at rest the hook or bent end of the lever or detent 142 will be in front of the pin 143 while the corresponding portion of the detent or lever 141 will be in a peripheral 50 notch in the disk 125. When the magnet 117 is energized the arms 115, and 138 and 139 are swung upward to the positions shown in Fig. 6 by reason of which the arm 139 will move the levers 141 and 142 to their 55 ineffective positions and thereby free the escapement mechanism. The hook of the arm 138 is also projected into the path of the projection 140. As the arm 115 is swung upward the pinion 113 is operated as previously described and at the same time the 60 pins 121 are revolved the said pins on such motion turning the spur-wheel 122 so as to carry the notch of the disk 125 away from the hooked end of the lever or detent 141.

65 It will be understood that at this time the

escapement mechanism is released but owing to the fact that the hook of the arm 138 is in the path of the projection 140 and the very small size of the pinions 133 and 135 the movement initially of the escapement 70 mechanism will be quite slight; almost imperceptible in fact. When, however, the magnet 117 is deenergized hooked arm or detent 138 will release the governor shaft 136 whereby the detent mechanism will freely 75 operate the consequence being that the gear or motor wheel 52 is also released and can turn one step, the wheel 130 of course moving one step which will be a distance corresponding to one tooth of the wheel 33, the 80 parts of the escapement mechanism being so proportioned as to assure this result. During the operation of the escapement mechanism after the same is released the levers 141 and 142 will be upheld by the unnotched 85 portion of the disk 125 this relation being maintained until the notch in said disk is brought opposite the hook of the lever 141 by the lantern-wheel 127 which operates the spur-wheel 122 for such purpose. The spur-wheel 122 is not normally in mesh with said lantern-wheel 127 or with the pins or teeth 121 by reason of which it may be freely oscillated as required.

It is believed the operation of the apparatus will be understood from the foregoing description in conjunction with the annexed drawings. Nevertheless a quite brief statement thereof will now be given: The operation of the printing-wheels or type-wheels 95 27, 27' and 27'' is wholly automatic. It will be assumed that a workman has arrived at his shop and that he desires to obtain a record of the time of the commencement of his work. He will if necessary first shift the card-receiving device 18 laterally to cover the particular time of day upon which he starts his labor and afterward insert his card into said card-receiving device. Or the card 100 may be first introduced into said card-receiving device and the latter then shifted sidewise. When the card is in the card-receiving device it will be arrested at the requisite place by the automatically-movable stop 73 which will indicate to the workman that the card is in condition to receive an impression. The printing of the card is accomplished by the action of the hand-lever 98 in the manner hereinbefore set forth. When a record is obtained the card can be 110 105 lifted from the card-receiving device.

I will hereinafter describe more particularly the operation of the escapement mechanism as it plays an important part in the accurate action of the apparatus.

115 My invention involves broadly printing mechanism and means for actuating the printing-mechanism, the actuating mechanism having means associated therewith for causing the printing mechanism to move a 120 125 130

distance equaling the time said printing mechanism may be arrested on the abnormal stoppage thereof. For illustration, a workman may arrive on time and may obtain a 5 printed record on his card to this effect. He may desire to secure the same record for a friend who anticipates being tardy. To accomplish this result the first workman will surreptitiously arrest the printing mechanism so that his companion may obtain the same time record. This is not possible with 10 the present apparatus for as soon as the printing mechanism is released it is immediately operated to catch up or compensate 15 for the time it may have been stopped and while as understood I do not limit myself to any particular means whereby this result can be attained the escapement mechanism to which I have alluded is advantageous 20 for the purpose.

During the normal operation of the apparatus the wheel 52 is operated step by step and the same statement applies with respect to the printing mechanism which is actuated 25 from said wheel. The step-by-step operation of the wheel 52 is made possible by the presence of the escapement mechanism. The wheel 122 as will be remembered is oscillatory. The normal oscillation thereof 30 is quite slight each stroke corresponding to one tooth of said wheel. The said wheel is advanced by the action of the magnet 117 while it is turned backward or retracted by the power of the motor-wheel 52, both said 35 parts acting upon said wheel 122 through intermediate means. It will be assumed that the printing mechanism is arrested for illustration by the placing of a weight on the lever or arm 98. The escapement mechanism 40 continues to operate and at each step the wheel 122 is advanced carrying the notch in the stop wheel or disk 125 which it will be remembered is rotative with said wheel 122. Therefore while the printing mechanism is 45 thus held out of action the wheel 122 is being advanced step by step. When however the printing mechanism is freed or released a retractive movement can be imparted to the wheel 122 and disk 125, and the amount 50 of movement backward of said wheel will correspond with the time that the printing mechanism has been held up, the backward movement of the wheel 122 continuing until the operative or hook portion of the detent 55 141 falls into the notch of the stop disk 125 at which point the normal action of the apparatus follows.

Referring now to Fig. 13 I show an indicating means for indicating different conditions of work for instance day's work, over time, piece work, over time, symbols indicating these conditions being marked on the casing of the apparatus and under each are arranged the words "In" and "Out" as 60 hereinbefore described. In connection with 65

such indicating means are the swinging arm or index-device 85', stops 86', and stop-holes 87' as hereinbefore described. This indicating means is employed where a card of the character illustrated in Fig. 1b is 70 used. The arm 85' of course has a greater sweep or stroke than the arm 85 and it naturally follows that the card-receiving device used in conjunction with an arm as 85' will have a greater movement than one employed 75 in connection with the arm 85.

What I claim is:

1. In a recording apparatus, the combination of printing mechanism, a card-receiving device movable toward and from the 80 printing mechanism to obtain an impression and also laterally movable to vary the lateral position of the imprint of the printing mechanism on the card, time controlled mechanism for operating said printing 85 mechanism, and means movable step by step by said time controlled mechanism, for arresting the card in said card-receiving device.

2. In a recording apparatus, the combination of printing mechanism, a card-receiving device movable toward and from the printing mechanism to obtain an impression therefrom and laterally movable to vary the lateral position of the imprint on the card, 95 time controlled mechanism for operating said printing mechanism, a stop for arresting the card while in said card-receiving device, a cam for operating said stop, and mechanism intermittently operable by said 100 time-controlled mechanism for operating said cam.

3. In a recording apparatus, the combination of printing mechanism, a card-receiving device one of said parts being movable 105 with respect to the other to obtain a record on the card and to also vary the lateral position of the record on said card, time-controlled mechanism for operating said printing mechanism, and means operable step by 110 step by said time-controlled mechanism for arresting the card.

4. In a recording apparatus, the combination of printing mechanism, a card receiving device movable toward and from the 115 printing mechanism to secure an impression on the card and also laterally movable to vary the lateral position of the imprint, time-controlled mechanism for operating the printing mechanism, a stop for arresting the 120 card, a snail-cam for actuating said stop, and means intermittently operable by the time-controlled mechanism for turning said cam.

5. In a recording apparatus, the combination of printing mechanism, a card-receiving device movable toward and from the printing mechanism to secure an impression and also laterally movable to vary the lateral position of the imprint, time-controlled 125 130

means for operating the printing mechanism, a stop for arresting the card, a stepped cam for actuating said stop, and means intermittently operable by the time-controlled mechanism for turning said cam step by step.

6. In a recording apparatus, the combination of printing mechanism, a card-receiving device movable toward and from the printing mechanism to secure an impression and also laterally movable to vary the lateral position of the imprint, time controlled means for operating the printing mechanism, speed-reducing gearing operable from the time-controlled mechanism, a cam, a spring-controlled oscillatory device operable by said cam, pawl and ratchet means operable by said oscillatory device, a cam operable by said pawl and ratchet means, and a stop for the card operable by said last mentioned cam.

7. In a recording apparatus, the combination of printing mechanism, a chute-like card receiving device, cross bars through which the card-receiving device passes, wheels on the cross-bars, the framework having means for supporting said wheels for traveling movement to permit the card-receiving device to move toward and from the printing mechanism, wheeled arms connected with the card-receiving device and the wheels of which are movable against said cross-bars longitudinally thereof to vary the lateral position of the card-receiving device, and time-controlled means for effecting the action of the printing mechanism.

8. In a recording apparatus, the combination of printing mechanism, time-controlled mechanism for operating the printing mechanism, a card receiving device movable toward and from the printing mechanism to secure an impression on the card and also laterally movable to vary the lateral position of the imprint both movements of the said card-receiving device being also straight paths, and stop-means for the card, movable step by step by said time-controlled mechanism.

50 9. In a recording apparatus, the combination of printing mechanism comprising several printing wheels, time controlled mechanism for operating the printing mechanism, detents for normally locking said printing wheels, the time-controlled mechanism having means to operate the respective detents to release said printing wheels, a card-receiving device movable toward and from the printing mechanism and also laterally movable, and card-arresting means movable step by step by said time-controlled mechanism.

10. In a recording apparatus, the combination of printing mechanism, a card-receiving device movable toward and from the

printing mechanism and also laterally movable along straight paths, a swinging impression member for moving the card-receiving device toward the printing mechanism, manually-operable means for swinging said impression member, means operative directly against said card receiving device, for moving the same laterally, time-controlled means for operating said printing mechanism, and mechanism operable step by step by the time controlled mechanism for arresting a card in said card-receiving device. 70

11. In a recording apparatus, the combination of printing mechanism, a card-receiving device movable toward and from the printing mechanism and also laterally movable along straight paths, an oscillatory impression member for moving said card-receiving device toward the printing mechanism, an eccentric for actuating said oscillatory device, a rack fastened to said card receiving device, and a shaft supported by fixed bearings and provided with a pinion meshing with said rack for moving the card-receiving device laterally. 80

12. In a recording apparatus, the combination of printing mechanism, and mechanism for actuating and for controlling the printing mechanism and including escapement means, the escapement means comprising an oscillatory wheel and other wheels for alternately operating said oscillatory wheel in opposite directions. 95

13. In a recording apparatus, the combination of printing mechanism, and means for actuating and for causing a step by step action of the printing mechanism and including escapement mechanism comprising an oscillatory wheel, other wheels for alternately operating the oscillatory wheel in opposite directions, and a detent for normally preventing movement of said oscillatory wheel. 100

14. In recording apparatus, the combination of printing mechanism, escapement mechanism, and means for operating the escapement mechanism step by step, and transmitting mechanism between the escapement and printing mechanisms for normally causing a step by step action of the printing mechanism and for permitting a continuation of such action when the printing mechanism is held out of action, the printing mechanism when released serving to impart a reverse movement to said transmitting mechanism. 110

15. In a recording apparatus, the combination of printing mechanism, means for normally operating the printing mechanism, a stop wheel mounted for oscillation, means for advancing the stop wheel, means co-operative with the printing mechanism operating means for retracting said wheel, and detent means coactive with said wheel. 125

16. In a recording apparatus, the combination of printing mechanism, a motor for normally operating the printing mechanism, a wheel mounted for oscillation, having a notch, means for advancing said wheel, means coöperative with the motor for retracting said wheel, and detent means normally disposed in the notch.
17. In a recording apparatus, the combination of printing mechanism and operating means therefor, escapement mechanism, and means coöperative with the printing mechanism and with the escapement mechanism for causing normally the intermittent operation of the printing mechanism and for permitting the operation of the escapement mechanism when the printing mechanism is held out of action.

18. In a recording apparatus, the combination of printing mechanism, escapement mechanism, and means coöperative with the printing and escapement mechanisms for causing normally the intermittent motion of the printing mechanism and at the same time a back and forth motion of the escapement mechanism and for also causing the forward motion solely of the escapement mechanism when the printing mechanism is held out of action.

In testimony whereof I affix my signature in presence of two witnesses.

JULIUS A. OLMSTED.
